DESIGN FOR A COMBINATION BEVELER AND SQUARER FOR FLAT AND CURVED PLATES

Michael Annick, Scranton, Pa., assignor, by
mesne assignments, to Wesel Manufacturing
Company, a corporation of Pennsylvania

Application July 24, 1934, Serial No. 52,679

Term of patent 14 years

To all whom it may concern:

Be it known that I, Michael Annick, a citizen
of the United States, residing at 617 Harrison
Avenue, in the city of Scranton, county of Lacka-
wanna, State of Pennsylvania, have invented a
new, original, and ornamental Design for a Com-
bination Beveler and Squarer for Flat and
Curved Plates, of which the following is a speci-
fication, reference being had to the accompany-
ing drawing, forming part thereof.

Figure 1 is a side view of the combination beveler
and squarer showing my new design.

Figure 2 is a front view of the machine shown
in Figure 1.

I claim:

The ornamental design for a combination beveler
and squarer for flat and curved plates, as
shown.

MICHAEL ANNICK.
